UNITED STATES PATENT OFFICE.

PERCY E. BARKER, OF CLEVELAND, OHIO, ASSIGNOR TO THE VAN DORN IRON WORKS COMPANY, OF CLEVELAND, OHIO, A CORPORATION OF OHIO

DUMP TRUCK.

Application filed October 24, 1921. Serial No. 509,923.

To all whom it may concern:

Be it known that I, PERCY E. BARKER, a citizen of the United States, residing at Cleveland, in the county of Cuyahoga and State of Ohio, have invented certain new and useful Improvements in Dump Trucks, of which the following is a specification.

This invention relates to improvements in hoisting mechanism for dump trucks and the like.

This application is a companion case of my copending application Serial No. 500,621, filed Sept. 14, 1921.

The objects of this invention are to provide a dump truck in which the hoisting mechanism is so constructed and arranged that it will not cause such an increase in the elevation of the load containing body as to render inconvenient the loading of material into the same; more particularly to provide a housing in the bottom of the truck body to accommodate the hoisting mechanism which is supported upon the chassis at a point beneath the truck body; and furthermore to provide such a structure that hoisting mechanism having direct connection with the truck body can be employed, while at the same time preclude the necessity of increasing appreciably the ordinary elevation of the truck body.

Other objects of this invention will be apparent from the following description and claims when considered together with the accompanying drawings.

Fig. 1 is a side elevation of my improved device; Fig. 2 is a transverse section on line 2—2, Fig. 1; Fig. 3 is an end elevation of the operating connections; Fig. 4 is a plan view, partly broken away, of the casing which encloses the operating mechanism; and Fig. 5 is an elevation, partly broken away, of the hoisting mechanism assembled as a unit.

In the general view of my invention as illustrated in Fig. 1 the chassis is indicated by reference numeral 1, the body by reference numeral 2, and the swinging truck body by the reference numeral 3, it being understood that the hoisting mechanism might be operated by a suitable connection from the engine of the truck or other source of power. The hoisting mechanism which, as illus-

trated in Figs. 4 and 5, is assembled as a unit and applied as such to the chassis of the truck, is mounted upon the channel bars 4 and 5 which form part of the chassis. These channel bars may be braced in any suitable manner. The casing, indicated in a general way at 12 and which encloses the operating mechanism for raising and lowering the truck body, is afforded support at its forward portion by means of the brace bar 9 which is supported upon and affords a brace for the channel bars. As indicated in Fig. 2, the rear middle portion of the casing 12 is provided with a recess 12^a in its under face to allow clearance for the differential of the drive mechanism of the truck. As above stated, any suitable source of power may be employed for driving the shaft 14 and in the present case the sprocket 15 is shown as being mounted upon the front end of the shaft 14 for operation by a chain which in turn may be driven from the engine of the truck.

Splined upon the shaft 14 is the clutch member 16, which is adapted to be slid into and out of clutching engagement with the companion clutch members 17 and 18 which are freely mounted upon the shaft 14. The clutch member 17 carries the gear 19 which meshes with the gear 20 fixed upon the shaft 21 extending through the casing and which also carries the worm 22 meshing with the worm gear 23. Pinion gears 23^a mounted upon the shaft 24 mesh in turn with two gears 25 keyed to sleeves 27^a carrying pinions 27 and mounted on shaft 26 upon the opposite ends thereof. These two pinions 27 mesh with the gears 28 which are fixed upon the aligned but separate shafts 29. The shafts 29 have bearings at their outer ends in the supports 30 mounted upon the top of the channel bars 4 and 5 as part of the drive mechanism unit. Fig. 4 shows only one-half of the mechanism enclosed within the casing, but it will be understood that the structure of the pinions 27, the two shafts 29 and the gears carried thereby as well as the bearing therefor are alike. The purpose of this particular arrangement of aligned, separate shafts will appear later. The cover plate 32 is provided for the opening through the top of the casing 12 and

other suitable openings are also provided to permit access to the inside thereof. It will be understood that suitable means of mounting the several gears and shafts within the casing are also provided. With the drive connection just now described it will be seen that the shaft 14 will communicate driving motion from its gear 19 to gear 20, that is when the clutch member 16 is thrown into engagement with the clutch member 17. Through the meshing gears and pinions described, motion will be transmitted to the two aligned shafts 29 upon which are fixedly mounted the crank arms 33 which in turn are pivotally connected with the lever arms 34. The arms 34 are mounted at their other ends to turn on a suitable axis 35 mounted in suitable supports provided on the under side of the truck body by means of channel irons 36. As clearly shown in the drawings, the lever 34 has an angular form, the upper end portion 34^a extending at approximately 90° to the truck body throughout practically all stages of the hoisting and lowering operations.

With this arrangement, operation of the shaft 29 causes a swinging upward movement of the truck body which is pivotally mounted at 37 in the bearing supports 38 fixed to the top of the channel bars 4 and 5, at the rear ends thereof. The clutch 16 is controlled by means of the yoke member 40 carried by the rod 41 which is reciprocated back and forth by means of its connection 42 with the operating rod 43 which in turn has sliding movement through the casing. This clutch control mechanism is actuated by the operator from the front end thereof by any suitable lever connection, as for instance indicated at 45. The rod 43 carries a stop member 46 which is adapted to be engaged by the companion trip members 47 carried upon one face of the gear 28. This particular mechanism is for the purpose of automatically shifting the clutch member 16 from engagement with either of the companion clutch members 17 and 18 into neutral position so as to automatically stop the swinging movement of the truck body when it has reached its upper or lower limit of movement. The clutch member 16 is shown in Fig. 5 as occupying neutral position.

When the clutch member 16 is moved into engagement with the clutch member 18, the pinion 50 carried thereby is set into operation and transmits its motion to the meshing pinion 51 which in turn drives the meshing pinion 52 fixed upon the shaft 21. It will be understood that the additional or intermediate pinion in this particular gear combination effects a reversal of the direction of operation of the shaft 21 from that which is obtained when the drive is through the pinions 19 and 20. Thus the engagement of the clutch member 16 with the clutch

members 17 and 18 will effect driving of the shaft 21 in either one direction or the other.

From the above it will be seen that in order to raise the truck body the operator will actuate the lever 45 in the proper direction to bring the clutch member 16 into engagement with one or the other clutch member, whereupon the shafts 29 are set into operation. The crank arms 33 then move about the axis of the shafts 29 and the truck body is raised to the position of approximately 45° to the horizontal, as indicated in dotted lines in Fig. 1, the truck body being pivoted at a point near its rear end. The operator may dis-connect the clutch at any time by means of the lever 45 so as to stop the raising movement of the truck body or he may depend upon the means for automatically throwing the clutch member 16 into neutral position to thereby stop the swinging movement. When it is desired to lower the truck body, the clutch member 16 is moved into engagement with the other companion clutch member so as to operate the shafts 29 and cause the lever arms 33 and 34 to fold below the same, as illustrated in Figs. 1 and 2. The operator may at any time throw the clutch into neutral position so as to stop the truck body at any degree of inclination desired or he may depend upon the automatic means for throwing out the clutch at its lower limit of movement.

The description thus far is substantially the same as that of the invention covered by my companion co-pending application above referred to, except as to certain details including the mounting of the casing upon the chassis and the connection of the arms 34 to the truck body.

In the present case I have provided a housing in the underside of the truck body, the main portion of said housing being indicated at 53 while the middle portion thereof, which is somewhat deeper, is indicated at 54. The purpose of such housing is to accommodate the hoisting mechanism which is located directly under the truck body so the truck body when in loading position will not be too high for convenient loading of material over the side when the operator is standing on the ground. The bottom frame of the truck body indicated at 55 is also afforded support upon the wooden sleepers 4' and 5' on bars 4 and 5. As indicated in Fig. 1, the housing formed in the underside of the truck body gradually diminishes in depth toward the front of the truck body, although no particular design of housing is necessary.

From the above it will be seen that I have devised an arrangement whereby it is possible to employ a hoisting mechanism which has direct and positive connection with the

underside of the truck body without requiring the truck body when in loading position to be too high for convenient loading; which means that my improved device with the 5 hoisting mechanism located under the truck body possesses the advantages of this particular form and arrangement of mechanism without sacrificing any convenience in respect to loading. The real advantage of 10 such an arrangement will be fully understood when it is recalled that the top edge of the truck body must not be higher than approximately sixty inches from the ground for convenient loading of material over the 15 side edge of the truck body. Furthermore, the hoisting mechanism in my improved device is afforded increased protection from the elements and a decidedly neat appearance is also produced.

20 The truck shown in the drawings is frequently used for hauling garbage, a material which always packs down solidly while being hauled over rough pavements, and more than that quickly freezes up in winter, as a result 25 of all of which it discharges from the truck body when elevated as a solid mass, rather than trickling out gradually as occurs with a load of sand or earth. With the arrangements shown in the drawings the housing 30 in the bottom of the truck body is spaced rearwardly from its front wall, is narrower than the truck body, or in other words, spaced from both of its side walls, and moreover has its front portion formed on a gradual incline. The result is to reduce so far 35 as possible the cubic contents for the necessary housing for the truck elevating mechanism and thereby increase the truck capacity without interfering with the ability 40 of the truck to readily dump its contents. A mass of garbage in the truck body readily slides rearwardly over the inclined forward portion of the housing. Moreover, said housing, being located between the side 45 walls of the truck, acts as a sort of plow and splits or divides the rearwardly sliding mass of garbage so that it moves out more readily than if the housing extended the full width of the truck, this being true even 50 though the mass may be frozen.

What I claim is:

1. In a dump truck, the combination of a wheeled chassis, a load receiving body mounted thereupon for raising and lowering movement, and means supported upon said frame and under said body in the region of the rear wheels for raising and lowering said body, the bottom of said body being formed with a housing in the region of the rear wheels for accommodating said raising and lowering means.
2. In a dump truck, the combination of a chassis, a load receiving body mounted thereupon for raising and lowering movement, and lever mechanism supported upon
3. In a dump truck, the combination of a chassis, a load receiving body mounted thereupon for raising and lowering movement, and a hoisting mechanism unit including levers for raising and lowering said body, said unit being supported upon said chassis at a point approximately midway of the length of said body, and the bottom of said body being formed with a housing for accommodating said unit.
4. In a dump truck, the combination of a chassis, a load receiving body mounted thereupon for raising and lowering movement, hoisting mechanism including levers connected to said body and means supported upon said chassis for operating said levers, said mechanism being located under said body and at a point substantially midway of the length thereof, and the bottom of said body being provided with a housing for accommodating said mechanism.
5. In a dump truck, the combination of a chassis, a load receiving body mounted thereupon for raising and lowering movement, hoisting mechanism for said body located under the same, and a housing in the bottom of said body and spaced rearwardly from its front wall to accommodate said hoisting mechanism.
6. In a dump truck, the combination of a chassis, a load receiving body mounted thereupon for raising and lowering movement, hoisting mechanism for said body located under the same, and a housing in the bottom of said body and spaced rearwardly from its front wall to accommodate said hoisting mechanism, said housing being narrower than the body.
7. In a dump truck, the combination of a chassis, a load receiving body mounted thereupon for raising and lowering movement, hoisting mechanism for said body located under the same, and a housing in the bottom of said body and spaced rearwardly from its front wall to accommodate said hoisting mechanism, said housing having its forward portion inclined.
8. In a dump truck, the combination of a chassis, a load receiving body mounted thereupon for raising and lowering movement, hoisting mechanism for said body located under the same, and a housing in the bottom of said body and spaced rearwardly from its front wall to accommodate said hoisting mechanism, said housing being narrower than the body and having its forward portion inclined.
9. In a dump truck, the combination of a wheeled chassis, a load receiving body mount-

ed thereupon for raising and lowering movement, hoisting mechanism supported upon said chassis and under said body in the region of the rear wheels for raising and lowering said body, the bottom of said body being provided with a housing to accommodate said hoisting mechanism, said

housing being spaced rearwardly from the front wall of the body and being narrower than said body and having its forward portion inclined. ¹⁰

In testimony whereof I hereby affix my signature.

PERCY E. BARKER.
